United States Patent Office.

EDWIN J. TOOF, OF FORT MADISON, IOWA,

Letters Patent No. 77,130, dated April 21, 1868; antedated April 11, 1868,

IMPROVEMENT IN TRY-SQUARES.

The Schedule referred to in these Letters Patent and making part of the same.

TO ALL WHOM IT MAY CONCERN:

Be it known that I, EDWIN J. Toof, of Fort Madison, in the county of Lee, and State of Iowa, have invented a new and useful Improvement in Try-Squares; and I do hereby declare and make known that the following is a full, clear, and exact description of the same, reference being had to the accompanying drawings, and the letters and figures marked thereon, which form part of this specification.

The nature of my invention consists in the attachment or arrangement, in combination with a try-square, used for the purpose of testing corners or angles of lumber, to ascertain whether the same are exactly square, of an adjustable saw or other cutting-device, so that upon applying the square to the corner to be tested, and moving the aforesaid cutter, a cut is formed across the top of the board or its equivalent, whose bottom will always be at right angles with the vertical face of the board, when the same may be planed down, and the angle is right right-angled with a certainty which requires no further test.

To enable those skilled in the art to understand how to construct and use my said invention, I will proceed to describe the same with particularity, making reference in so doing to the aforesaid drawings, in which—

Figure 1 represents a side view of my invention.

A represents a try-square, one face of which may have both arms thereof in the same plane.

Upon one side thereof is arranged a saw or other edged device, which will cut into the wood as desired, marked B, which is provided with oblique slots b b, as shown, through which pass headed pins a, which are rigidly secured to the try-square A.

The cutting or toothed edge of B is always at right angles with the vertical arm of the square, and though lying above the angle of the square, as clearly seen in the drawings, yet upon being pressed forward by pressing upon the roughened thumb-piece C, or otherwise, the direction of the slots b b causes the cutting-edge to pass below the face of the square itself, so that should the angle upon which the square is applied be irregular, the edge of the cutter in the above operation will be caused to cut through the irregularities, forming a channel or cut across the top of the article being tested, whose bottom is at right angles with the vertical side of the same.

Upon removing the square and planing down the surface true with said line or cut so formed, the angle is invariably righted.

The cutter B may be secured to the square in any other suitable manner than the one herein described, provided the oblique downward movement be secured in the manner described.

Having described the construction and operation of my invention, I will now specify what I claim, and desire to secure by Letters Patent.

I claim, in combination with a try-square A, an adjustable cutter B, arranged and operating substantially in the manner and for the purposes set forth.

E. J. TOOF.
